(57) **CLAIM**

The ornamental design for a trocar housing, as shown and described.

DESCRIPTION

FIG. 1 is a perspective view of a trocar having a trocar housing, a cannula shown in phantom extending from the trocar housing, an obturator shown in phantom extending through the trocar housing and the cannula, and a stopcock shown in phantom located adjacent to the trocar housing;

FIG. 2 is a first side view of the trocar of FIG. 1;

FIG. 3 is a second side view of the trocar of FIG. 1; and

FIG. 4 is a third side view of the trocar of FIG. 1;

FIG. 5 is a fourth side view of the trocar of FIG. 1;

FIG. 6 is a top view of the trocar of FIG. 1; and,

FIG. 7 is a top view of the trocar housing of FIG. 1, with the obturator removed.

1 Claim, 4 Drawing Sheets

Related U.S. Application Data

continuation-in-part of application No. 12/533,590, filed on Jul. 31, 2009, now Pat. No. 8,568,362, which is a continuation-in-part of application No. 12/110,724, filed on Apr. 28, 2008, now Pat. No. 8,579,807, and a continuation-in-part of application No. 12/110,727, filed on Apr. 28, 2008, now Pat. No. 8,870,747, and a continuation-in-part of application No. 12/110,742, filed on Apr. 28, 2008, and a continuation-in-part of application No. 12/110,755, filed on Apr. 28, 2008, now Pat. No. 8,273,060.
